MOLDED SWIMSUIT BUOYANCY PAD

Louis Brumberger, New Haven, Conn., assignor to Teen-Age Beachwear Corporation, New York, N. Y., a corporation of New York

Application March 31, 1954, Serial No. 29,790

Term of patent 14 years

(Cl. D3—17)

Fig. 1 is a front view of a molded swimsuit buoyancy pad embodying my design;

Fig. 2 is a rear view thereof;

Fig. 3 is a side view thereof; and

Fig. 4 is a sectional view thereof taken on the line 4—4 of Fig. 1.

I claim:

The ornamental design for a molded swimsuit buoyancy pad, as shown.
